GRINDING MACHINE

Charles H. Amidon, Worcester, Mass., assignor to
 Norton Company, Worcester, Mass., a corpora-
 tion of Massachusetts

Application February 6, 1937, Serial No. 124,450

5 Claims. (Cl. 51—95)

This invention relates to grinding machines, and more particularly to a hydraulically operated cylindrical grinding machine.

One object of the invention is to provide a simple, thoroughly practical hydraulically operated grinding machine. Another object of the invention is to provide an improved control mechanism for a hydraulically operated grinding machine. Another object of the invention is to provide a hydraulically operated grinding machine with an interlocked fluid pressure and manual traverse control for the work table. Another object of the invention is to provide a hydraulically operated grinding machine with an interlock between the control for the fluid pressure reciprocating mechanism and the manual traversing mechanism. Another object of the invention is to provide a fluid pressure reciprocating mechanism for the work support which is controlled by a manually operable lever and arranged so that when the lever is thrown to an operative position, the manual table traversing mechanism will be rendered inoperative. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing, in which is shown one of various possible embodiments of the mechanical features of this invention,

Fig. 1 is a front elevation of the improved grinding machine;

Fig. 2 is a fragmentary front view, on an enlarged scale, of the manual and hydraulic table traverse controls, having parts broken away to show the interior construction;

Fig. 3 is a cross sectional view, on an enlarged scale, taken approximately on the line 3—3 of Fig. 1; and

Fig. 4 is a fragmentary diagrammatic piping arrangement of the fluid pressure table reciprocating mechanism.

A grinding machine embodying this invention comprises a base 10 which supports a longitudinally movable table 11 on the usual V way (not shown) and a flat way 9 for a longitudinal reciprocating movement relative to the base 10. A motor driven headstock 12 and a footstock 13 are mounted on the table 11 and are arranged rotatably to support a work piece on a headstock center 14 and a footstock center 15 in operative relation with a rotatable grinding wheel 16. The

grinding wheel 16 is rotatably supported on a transversely movable wheel slide 17, of the usual type, such as for example that shown in the expired United States patent to Norton No. 762,838 dated June 14, 1904. In the preferred form, an electric motor 20 is mounted on the wheel slide 17 and is provided with a pulley 21 which is connected by driving belts 22 with a pulley 23 on the end of a wheel spindle 24.

A fluid pressure mechanism is provided to reciprocate the table 11. In the form illustrated, a cylinder 30 is fixedly mounted to the under side of the table 11. The cylinder 30 contains a piston 31 which is connected by a pair of hollow piston rods 32 and 33, respectively, with a pair of hollow brackets 34 and 35, respectively, which are fixed on opposite ends of the base 10.

In the preferred construction, the base 10 is formed as a hollow, box-like construction in which the lower portion of the base serves as a reservoir 40 for the fluid pressure system. Fluid is drawn from the reservoir 40 through a pipe 41 by a pump 42 and is forced through a pipe 43 and a pipe 44 to a table control valve 45. A fluid pressure relief valve 46 is provided in the pipe 43 and is arranged to allow fluid under pressure to pass through a pipe 47 and return to the reservoir 40 in case the fluid pressure within the system increases above a desired pressure.

The control valve 45 has been illustrated only diagrammatically, since this feature is not considered to be part of the present invention. For a detailed disclosure of the control valve 45 and also the fluid pressure system, reference may be had to the United States Patent No. 2,071,677 to Wallace H. Wood dated February 23, 1937. The reversing valve 45 is arranged to combine the functions of a reversing valve and a pilot valve, so that a lever actuated by the table movement serves to move the valve only to a center position and then fluid under pressure serves to move the reverse valve into a reverse position, producing a smooth reversal of the table without the necessity of providing a complicated series of valve mechanisms and pipe connections. A pivotally mounted control lever 50 is carried by a stud 51 mounted on an apron 52 which is supported on the front of the machine base 10. The lower arm of the lever 50 is connected by a stud 53 with a valve stem 54 of the valve 45. The upper end of the lever 50 is arranged in the path of a pair of adjustable table dogs 55 and 56.

Fluid under pressure may pass from the control valve 45, through a pipe 60 and a pipe 61, through the bracket 35 and the hollow piston rod 55

33 and into a cylinder chamber 62 to move the cylinder 30 and the table 11 toward the right (Fig. 4). During the movement of the table toward the right, fluid exhausts from a cylinder chamber 63, through the hollow piston rod 32, a pipe 64, a pipe 65, into a chamber 66 in the control valve 45, and out through a pipe 67, through a throttle port 68 in a control valve 69, and exhausts through a pipe 70 into the reservoir 40. A valve piston 71 in the control valve 69 has an angled-off end face which may be rotated to regulate the aperture of the port 68 so as to control the speed of movement of the table 11. A valve stem 72 of the valve 69 is provided with a control knob 73 by which the valve may be rotated to control the table speed. The valve stem 72 is arranged so that the valve may be moved endwise from a stop to a start position by means of a control lever 75 which is pivotally mounted on a stud 76. The lever 75 is connected to the valve stem 72 so that the valve stem 72 may be moved endwise to open or close the port 68 to stop or start the fluid pressure movement of the table 11. When the control valve 69 is moved toward the left (Fig. 4) to stop the fluid pressure movement of the table, a by-pass groove 78 in the valve 69 connects the pipe 65 with the pipe 61 to permit by-passing of fluid between the cylinder chambers 62 and 63 to facilitate manual traversing of the table when desired.

A manually operable table traverse mechanism is provided for manually traversing the table 11 longitudinally relative to the base 10. This mechanism, as illustrated, is preferably of a two-speed type, such as that disclosed in the prior United States Patent No. 1,299,765 to Norton and Turner dated April 8, 1919. The table 11 is provided with a depending rack bar 80 which meshes with a gear 81 slidably keyed to a rotatable shaft 82. The shaft 82 is supported in bearings 83 and 84 in the apron 52. A large gear 85 is keyed to the outer end of the shaft 82. A manually operable hand traverse wheel 86 is rotatably mounted on an outwardly extending shaft 87 which is fixed to the apron 52. The hand wheel 86 carries a rotatable shaft 88 having formed integrally thereon a gear 89 which meshes with an internal gear 90. The gear 90 is mounted on the hub of a gear 91 which is rotatably mounted on the shaft 87. The shaft 88 rotatably supports a gear 92 meshing with a non-rotatable internal gear 93 which is fixed relative to the apron 52. When the hand wheel 86 is rotated to traverse the table 11, this motion is transmitted through the gear 89 to rotate the gear 90 at the same speed at which the hand wheel 86 is rotated to transmit a rotary motion through the gear 91 and through the gear 85 to rotate the shaft 82 and the gear 81 to cause a longitudinal traversing movement of the table 11.

The outer face of the gear 92 is provided with clutch teeth (not shown) which are arranged to be engaged by a clutch member 94 which is actuated by a knob 95. The clutch member 94 is slidably keyed to the shaft 88 and is arranged to be moved into and out of operative engagement with the clutch teeth on gear 92 by means of the knob 95. If a slow traversing movement of the table is desired, such as for traversing a diamond or truing tool at a slow uniform rate across the face of the grinding wheel 16, the knob 95 is pushed toward the left (Fig. 3) so that the clutch member 94 is thrown into engagement with the clutch teeth on the gear 92. In this position of the parts, rotation of the hand wheel 86 revolves

the gears 89 and 92 and the shaft 88. The pinion 92 meshing with the fixed internal gear 93 is thereby forced to rotate, turning the gear 89 with it, which in turn rotates the internal gear 90 and causes a differential movement between the parts, this movement being transmitted to the gears 91 and 85 to rotate the shaft 82 at a slow speed, which motion is transmitted through the gear 81 to the rack 80. Full details of this mechanism have not been illustrated or described in the present case, since this feature in itself is not considered part of the present invention. For complete details of construction of the manually operable table traverse mechanism, reference may be had to the above-mentioned United States Patent No. 1,299,765.

It is desirable to provide a suitable interconnection between the hydraulically operated table reciprocating mechanism and the manually operable traverse mechanism so that when the table 11 is reciprocated by means of the table control fluid pressure mechanism, the manually operable traverse mechanism will be rendered inoperative so that the manually operable traverse wheel 86 remains stationary during the power reciprocation of the table 11. This is preferably accomplished by slidably keying the gear 81 on the shaft 82 so that it rotates therewith but may be moved endwise into and out of mesh with the rack bar 80. A spring 100 surrounds the shaft 82 and is interposed between the gear 81 and a flange 101 on the shaft 82. The compression spring 100 normally holds the gear 81 in mesh with the rack 80. A head 102 on the end of the shaft 82 serves to locate the gear 81 relative to the rack 80 and to limit its motion when thrown into mesh therewith.

In order to throw the gear 81 out of mesh with the rack 80 when desired, a bell crank lever 105 is pivotally mounted on a stud 106 within the base 10 of the machine. The upper end of an arm 107 of the bell crank lever 105 is formed as a yoked member 108 which straddles a hub on the gear 81. The yoked member 108 is provided with diametrically opposed, inwardly projecting pins 109 which ride in a groove 110 in the hub of the gear 81. It will be readily appreciated that when the bell crank lever 105 is rocked in a clockwise direction (Fig. 3), gear 81 will be moved against the compression of the spring 100 into dotted line position 81a, out of mesh with the rack bar 80.

In order to disengage the gear 81 when the control lever 75 is thrown into the position illustrated in Fig. 4 to start the table traverse under fluid pressure, a cam mechanism is provided which is actuated by the control lever 75. A lever 120 (Fig. 3) is mounted on the stud 76 and is either formed integral with or fixed to the lever 75 so that when the lever 75 is shifted, the lever 120 will be moved through a corresponding extent. A cam 121 is formed on the upper end of a lever 122 which is pivotally mounted on a stud 123 carried by the base 10. The cam 121 is arranged to engage a follower roller 124 carried on an arm 125 of the bell crank 105. The lower end of the lever 122 is connected by a stud 126 with one end of a link 127. The other end of the link 127 is connected by a stud 128 with the lower end of the lever 120. When the lever 75 is moved in a clockwise direction (Fig. 2) to open the control valve 69 and start the movement of the table under control of the fluid pressure mechanism, the lever 120 is also rocked in a clockwise direction, causing the link 127 to move toward the left 75

(Fig. 3), thereby rocking the lever 122 on its supporting stud 123 in a clockwise direction. This movement causes the cam 121 to move in a clockwise direction, which in turn transmits a clockwise rocking movement of the bell crank 105 to throw the gear 81 out of mesh with the rack 80, thereby rendering the manually operable hand wheel 86 inoperative and allowing it to remain stationary during the fluid pressure traversing or reciprocating movement of the table 11.

The cam 121 is so shaped that when the lever 122 is moved in a clockwise direction (Fig. 3), the rise on the cam causes the bell crank lever 105 to be rapidly moved in a clockwise direction, thereby quickly disengaging the gear 81 from the rack 80. The cam 121 is provided with a portion which is concentric with the stud 123 which serves to lock the bell crank 105 against the compression of the spring 100 so as to hold the gear 81 out of mesh with the rack 80 until the control lever 75 is again shifted to stop the fluid pressure reciprocating movement of the table 11.

The grinding wheel slide 17 and grinding wheel 16 are arranged for a transverse feeding movement to feed the wheel toward or from the work piece being ground to produce the desired feeding action. A manually operable feed wheel 120 is mounted on the front of the machine base and is operatively connected through a gear mechanism and nut and screw mechanism (not shown) to feed the grinding wheel transversely as desired. The details of this mechanism have not been fully illustrated in the present application since this feeding mechanism is not considered a part of the present invention. This feed is substantially identical to that shown in the prior United States patent to Norton No. 762,838 dated June 14, 1904, to which reference may be had for further details of construction. The feed wheel 120 may be operated manually or, if desired, it may be actuated by means of a feed pawl 121.

The operation of this mechanism will be readily apparent from the foregoing disclosure. When it is desired to traverse the table manually, the control lever 75 is positioned as illustrated in Fig. 3, so that the gear 81 is in mesh with the rack 70. In this position of the parts, the hand wheel 86 may be rotated and through the two-speed mechanism above described, the table 11 may be traversed either at a comparatively slow rate or at a fast rate, as desired. When it is desired to traverse or reciprocate the table 11 by the fluid pressure mechanism, the control lever 75 is rocked in a clockwise direction from the position illustrated in Fig. 3 into the position illustrated diagrammatically in Fig. 4, which serves to open the port 68, thereby starting the table reciprocation by fluid under pressure. During the shifting movement of the control lever 75, the cam 121 rocking in a clockwise direction rocks the bell crank lever 105 also in a clockwise direction to disengage the gear 81 from the rack 80, thereby rendering the manually operable traverse mechanism inoperative and allowing the hand wheel to remain stationary during the power traverse of the table.

It will thus be seen that there has been provided by this invention apparatus in which the various objects hereinbefore set forth together with many thoroughly practical advantages are successfully achieved. As many possible embodiments may be made of the above invention and as many changes might be made in the embodiment above set forth, it is to be understood

that all matter hereinbefore set forth or shown in the accompanying drawing is to be interpreted as illustrative and not in a limiting sense.

I claim:—

1. In a grinding machine, a longitudinally movable table, a hydraulically operated reciprocating mechanism therefor, a stop and start valve to control the hydraulic mechanism, a manually operable control lever to actuate said valve, a manually operable table traverse mechanism including a rotatable hand wheel and a rack and gear mechanism, said gear being arranged to move into and out of mesh with said rack, yieldable means normally to maintain said gear in mesh with said rack, means including a pivotally mounted cam operatively connected to move said gear out of mesh with said rack, and connections between said lever and cam whereby the cam is moved to disengage said gear when the lever is moved to start the hydraulic table traversing mechanism, said cam being arranged to lock said gear out of engagement with said rack during the hydraulic traversing movement.

2. In a grinding machine, a longitudinally movable table, a hydraulically operated reciprocating mechanism therefor, a stop and start valve to control the hydraulic mechanism, a manually operable control lever to actuate said valve, a manually operable table traverse mechanism including a rotatable hand wheel and a rack and gear mechanism, said gear being slidably mounted so that it can be moved into or out of mesh with said rack, a spring normally to maintain said gear in mesh with said rack, a pivotally mounted bell crank lever, a yoke formed on one arm of said bell crank lever which is operatively connected to move said gear, a follower roller on the other arm of said bell crank lever, a pivotally mounted cam, and a link connecting said cam with said control lever whereby said cam rocks said bell crank lever to throw the gear out of mesh with the rack when the control lever is moved to start the hydraulic table traversing movement, said cam being arranged to lock said gear out of mesh with the rack during the hydraulic traversing movement.

3. In a grinding machine, a longitudinally movable table, a hydraulically operated reciprocating mechanism therefor, a stop and start valve to control the hydraulic mechanism, a manually operable control lever to actuate said valve, a manually operable table traverse mechanism including a rotatable hand wheel and a rack and gear mechanism, yieldable means normally to maintain said gear in mesh with the rack, means including a bell crank lever operatively connected to move said gear out of mesh with the rack, and means including a cam actuated by said lever to move said bell crank lever to shift the gear out of mesh with the rack when the hydraulic table reciprocation is started, said cam being so shaped and arranged as positively to lock said gear out of mesh with the rack during the hydraulic table traversing movement.

4. A grinding machine comprising a rotatable grinding wheel, a rotatable work support, a longitudinally movable table for said support, means to move said grinding wheel and work support transversely relative to each other, manually operable means including a rack and gear mechanism to traverse said table longitudinally, yieldable means normally to maintain said gear in mesh with said rack, a fluid pressure system including a piston and cylinder operatively connected to reciprocate said table longitudinally,

means including a reversing valve to change the direction of movement of the table, a control valve which serves in one position to control the speed of movement of the table and in a second position to stop the flow of fluid to and from said table and to permit by-passing fluid from one end of the cylinder to the other, a manually operable lever to actuate said control valve, and a cam actuated by said lever to throw said gear out of mesh with the rack when the control valve is opened to start the table movement.

5. A grinding machine comprising a rotatable grinding wheel, a rotatable work support, a longitudinally movable table for said support, means 10 to move said grinding wheel and work support transversely relative to each other, manually operable means including a rack and gear mechanism to traverse said table longitudinally, a spring normally to hold said gear in mesh with

15 said rack, a fluid pressure system including a piston and cylinder operatively connected to reciprocate the table longitudinally, means including a reversing valve to change the direction of movement of the table, a control valve which serves in one position to control the exhaust of fluid from said cylinder to regulate the power movement of said table and in a second position to shut off said fluid flow and to permit a by-pass of fluid from one end of the cylinder to the other 10 during a manual traverse of said table, a pivotally mounted bell crank lever operatively connected to move said gear against the tension of said spring, a manually operable lever operatively connected to actuate said valve, and a cam actuated by said lever to rock said bell crank when said control valve is moved to an open position to throw said gear out of mesh with said rack.

CHARLES H. AMIDON.
